(57) **CLAIM**

The ornamental design for a light emitting diode, as shown and described.

DESCRIPTION

FIG. 1 is a perspective view of a light emitting diode showing our new design;

FIG. 2 is a top plan view thereof;

FIG. 3 is a bottom plan view thereof;

FIG. 4 is a front elevational view thereof; the rear elevational view is a mirror image thereof;

FIG. 5 is a right side elevational view thereof; the left side elevational view is a mirror image thereof; and,

FIG. 6 is an enlarged view thereof taken along the line 6-6 in FIG. 2.

The dashed broken lines in the drawings are for the purpose of illustrating unclaimed portions of the light emitting diode and form no part of the claimed design, and the dash-dot-dash broken lines in the drawings illustrate the boundary of the claimed design.
